ABSTRACT: A device consists of a plurality of rings which are constrained by separator means in vertical spaces permitting limited lateral movement as well as up and down movement, and a rod which passes through the rings. In alternate embodiments the rod is movable to a plurality of positions to control the contact of the rings with a thread passing therethrough.

THREAD TENSIONER

BACKGROUND OF THE INVENTION

This invention relates to tensioners, and more particularly to tensioners of the type having a plurality of rings which are relatively free floating in their disposition in the tensioner, and which, in effect, hang on the thread line thereby exerting a force on the line transverse to its direction of movement through the tensioner, and accordingly imparting a tension in the line.

The basic ring-type tensioner as is known in the art, consists of a plurality of rings which hang on the thread line passing through the tensioner, which rings are separated by spacer bars. To my knowledge there are no tensioners of the ring-type which employ any means for adjusting the position of the rings with respect to the thread line so as to vary the forces on the line. Depending on such factors as the type of textile material being processed, such as thread, yarn, cord, etc., the twist in the material, the crimp in the material, the denure of the material, and the speed at which it is being processed, the effect of a given set of tensioning rings, insofar as their ability to impart a constant or uniform tension to the textile material is concerned, can vary greatly. Under certain conditions, the jumping and rotating of the rings is so violent that, as a practical matter, tension in the textile material is not controlled at all. Accordingly, I have recognized a need in the prior art for some means of controlling the movement and disposition of the rings with respect to the textile material passing through the tensioner, so as to control the tension in said material.

SUMMARY OF THE INVENTION

I have provided, and disclosed in this application, an improved ring tensioner comprising a body having means thereon for guiding a strand of textile material therethrough, a plurality of rings arranged so that said material passes through said rings, said rings being normally in contact with said material during processing thereof, a plurality of ring separators to separate and confine as to lateral movement said rings, and a bar mounted to said body and engaging said rings to effect the position of said rings with respect to said textile material. In the preferred embodiment of my invention, the bar extends through said rings and is pivotally mounted and connected to a lever arm to pivot said bar and thereby guide said rings in an arcuate path with respect to said textile material. The lever arm is preferably adjustable to a plurality of predetermined fixed positions. In an alternate embodiment, the bar is laterally retractable to release the rings from engagement therewith.

Accordingly, an object of this invention is to provide an effective means for controlling the position of the rings in a ring tensioner whereby the tension in the textile material being processed can be varied within acceptable limits.

This and other objects of the invention will become apparent from the following description with reference to the accompanying drawings.

BRIEF DESCRIPTION OF THE DRAWINGS

FIG. 1 is a plan view of a ring tensioner in accordance with a preferred embodiment of my invention;

FIG. 2 is a view taken as indicated by the lines and arrows II-II in FIG. 1;

FIG. 3 is a view taken as indicated by the lines and arrows III-III in FIG. 1, showing alternate positions in phantom;

FIG. 4 is a plan view of an alternate embodiment of my invention;

FIG. 5 is a view taken as indicated by the lines and arrows V-V in FIG. 4;

FIG. 6 is a view similar to FIG. 5 showing a portion of the device in alternate position;

FIG. 7 is a view taken as indicated by the lines and arrows VII-VII in FIG. 4 with a portion of the device shown in phantom alternate positions;

FIG. 8 is a side view of an alternate embodiment of my invention; and

FIG. 9 is a plan view of the embodiment shown in FIG. 8.

DESCRIPTION OF THE PREFERRED EMBODIMENTS

Although specific forms of the invention have been selected for illustration in the drawings, and the following description is drawn in specific terms for the purpose of describing these forms of the invention, this description is not intended to limit the scope of the invention which is defined in the appended claims.

Referring to FIG. 1 the ring tensioner in accordance with one embodiment of my invention comprises a body 10 which can be adjustably mounted to any suitable support means 11 by means of the bracket portion 12 and a setscrew 13. In the embodiment shown, the tensioner consists of two sets of rings; each set being independently controlled as will be more fully explained hereinafter. It should be understood that the number of rings in a set or the number of sets in a particular tensioner can be varied within the scope of this invention without departing from the true spirit thereof. Accordingly, I shall describe in detail only the set designated generally 14, it being understood that similar parts perform similar functions in the remaining sets.

The set 14 consists of three rings, 15, 16, and 17 which for practical purposes, are identical, circular in cross section and overall configuration, and preferably made of a ceramic material (as is well known in the art). The rings are disposed in the tensioner so as to be relatively free floating; that is, while they at times contact or engage other parts of the device or the material passing therethrough, they are not fixedly connected to any other part of the device. The rings, however, are spaced from one another, and are confined to move only within the space laterally bounded by the separator rings 18, 19, 20, and 21. They are vertically controlled by the laterally extending portion 25 of the tension control bar designated generally 24.

Referring as needed to FIGS. 1, 2, and 3, the separator rings are preferably U-shaped members formed from metallic wire or similar material, and fixedly connected to the base 30 to form a rigid structure for confining the lateral motion of the adjacent ring. Disposed inwardly from the outer separator ring 21 and in the same vertical plane, there is an inner separator ring 22 of a similar configuration and construction also fixedly attached to the base 30. A similar inner separator ring is provided for each of the outer separator rings 18, 19, and 20.

Extending outwardly from the base 30 are a pair of flanges 31 and 32. Each flange supports a thread guide or eye 33 and 34 respectively which is preferably made of a ceramic material, but can be of any suitable material and design as is well known in the art, for guiding the textile material, whether it be thread, yarn, cord, or the like through the tensioner.

Additional similar-type thread guides 35 and 36 are provided mounted on flanges connected to the body 10 and preferably disposed at acute angles to the direction of travel of the textile material through the ring portion of the tensioner. The guide 35 can be conveniently referred to as the balloon breaker eye since it is associated with a relatively large, preferably circular, plastic disc 38, known in the art as a balloon breaker, which is fixedly attached to the flange on the body 10 for the purpose of controlling and guiding the yarn as is well known in the art.

The flanges 31 and 32 also support the tension control bar 24. The bar consists of a laterally extending rod 25 which doglegs at either end to end portions 26 and 27 which are pivotally mounted in the flanges 31 and 32 respectively. Lever arm 28 is fixedly connected as at 29 to portion 27 of the control bar 24, so as to pivot the control bar in its mountings upon movement thereof.

The textile material 40 is threaded through the device in the direction of the arrows so that it passes through the rings. To make it easy to accomplish this step, the lever arm 28 is placed in the "park" position shown in FIGS. 1 and 2, thereby moving the tension control bar to the position shown wherein it supports the rings in an arrested position slightly eccentric to the eye 33.

In order to bring the rings into engagement with the textile material, the lever arm is swung on an arc as shown by the arrow in FIG. 3. In this embodiment the tension control bar can be rotated more than 180° if necessary so that it could assume the position of bar 124, FIGS. 1 and 3. As the bar 124 is swung from its position shown in phantom to its position shown in full lines, the set of rings designated generally 44 move from the upper position shown in phantom to the position shown in full lines wherein they are in engagement with the textile material 40, and no longer engage the laterally extending rod 125. In such position, the rings exert a force transverse to the direction of travel of the textile material through the tensioner, and thereby impart a tension to the textile material. Should the material break or run out, the rings would drop onto the bar 125 as shown in the lower phantom position, FIG. 3.

Referring to FIGS. 4 through 7, I shall now describe an alternate embodiment of my invention wherein means are provided for adjustably positioning the tension control bar to a plurality of predetermined fixed positions. The tensioner shown comprises a body 210 on which there is mounted a frame including a base 230 and outwardly extending flanges 231 and 232. Each flange supports a thread guide as at 233 and 234, similar to those previously described. A set of six rings are provided designated generally 214, the rings being separated by outer and inner separator rings as previously described. The tension control bar designated generally 224 comprises a laterally extending rod 225 which is doglegged to end portions which are pivotally mounted in the flanges 231 and 232. A lever arm 228 is fixedly connected to the pivotally mounted portion of the tension control bar to move the bar upon movement of the lever arm. Once again, the rings are disposed about the laterally extending rod 225 so as to rest thereon when no textile material is present in the device.

In this embodiment the flange 231 has an extended, thickened portion 239 which is notched out to provide a series of notches for receiving the lever 228 as shown in FIGS. 5, 6, and 7. The lever is preferably made of a spring steel wire material, and while it is relatively rigid, it can be easily bent to the right in FIG. 4, so that it will clear the raised portion 239, and can be moved to various positions as shown in phantom in FIG. 7, wherein, once it is released, it springs back into one of the adjacent notches. The position of the rings can be effected within a limited range by the position of the tension control bar in accordance with the predetermined position of the lever in the notched portion of the flange 231. Compare FIG. 5 with the phantom position shown in FIG. 6.

When textile material, such as the thread line 240, is threaded through the guides and rings of a device as shown in FIG. 4, and the tension control bar is moved from its top dead center position toward its lower position, the rings soon come in contact with the thread line as shown in FIG. 5. As the control bar moves further down, more tension will be put upon the thread line. By virtue of the fact that the ring is free to pivot around the control bar, the ring will tend to shift from a position wherein it hangs solely from the laterally extending rod 225 (as shown in phantom in FIG. 6) to a position wherein it hangs on both the rod 225 and the thread line 240. As the bar is moved further down, the load can be increased on the thread line and conversely as it is moved closer to the top position, the tension will be reduced. Further, note that even though the rings are in contact with the tension control bar, they are not connected to it, and remain relatively free floating. Thus, the rings can relieve themselves when snagged for jumping in response to the moving line 240.

As previously mentioned, the number of rings in a set of rings can be varied as desired and the number of sets in a tensioner also can be varied. I have illustrated herein two variations which provide a measure of control over the tension applied by the rings to the textile material being fed through the device. In the embodiments shown in FIGS. 1 through 3 both sets of rings can be placed in contact with the textile material 40 so that it is acted upon by the full weight of six rings. Alter-

natively, the set of rings, designated generally 14, can be removed from active contact with the textile material 40 by placing the lever 28 in the parking position shown in FIGS. 1 and 2. For this purpose the lever 28 is conveniently bent to rest upon the body 10 and thus it will remain in the "park" position until forcibly rotated.

In the embodiments shown in FIGS. 4 through 7, a greater measure of control can be exercised by use of the means for fixedly positioning the lever arm in a plurality of predetermined positions wherein a set of rings can be placed in various fixed positions exerting more or less force on the textile material depending on the disposition of the rings with respect to the line of movement of the material.

In a still further embodiment of my invention as shown in FIGS. 8 and 9, the disposition of a single ring with respect to the thread line can be effected. Here the design of the body and spacer elements have been changed significantly so that a further detailed description is necessary. Accordingly, referring to FIGS. 8 and 9 as needed, the device comprises a body 310 which can be mounted in any convenient manner as previously described. The body has upwardly extending flanges 311 and 312, having guide eyes 313 and 314 disposed therein to guide the thread lines through the device. A plurality of spacer bars 315 preferably circular in cross section and made of ceramic material as is well known in the art, are spaced longitudinally along the body 310 and are supported at their ends in the side walls of the body 310. In the embodiment shown, there are six ceramic rings 320, 321, 322, 323, 324, and 325, disposed in spaced relation alternating with the spacer bars. Fixedly attached to the sidewall 328 is a mounting bracket 329 which supports an inwardly extending terminal guide 330. The terminal guide 330 has a laterally extending hole therethrough, the axis of which is parallel to the coincident axes of the guides 313 and 314.

To exercise control over the position of the rings, I have provided a laterally extending bar 340 which is disposed in sliding engagement in a bearing 341 fixedly mounted in the flange 311 and positioned so as to be axially aligned with the hole in the terminal guide 330. When the bar is moved to the right, the end thereof extends into the hole so as to be supported by the guide 330 as shown in the phantom position. The bar is conveniently provided with a handle means 342 at one end which is preferably hooked as at 343 at its free end so that it can be locked in position about the flange 311 when it is fully inserted into the device as shown in the phantom position.

In the embodiments shown, the bar is designed to support three of the six rings. As the bar is retracted to the left, FIGS. 8 and 9, the rings are released sequentially and fall into engagement with the thread line 350. Refer to the position shown in the FIGS. wherein the ring 322 is no longer supported by the bar 340 and has now become engaged with the thread line 350. Conveniently, additional locking means 355, 356 are provided for frictionally engaging the hook 343 on the bar 340 and maintaining it in its extended position so that the number of rings released may be determined selectively and the remaining rings permanently retained.

It will be understood that the particular arrangement shown represents the preferred embodiment and accordingly the bar 340 has been designed to support only some of the rings in the tensioner, since it is normally desirable to have at least some rings in contact with the thread line during all phases of operation. However, it is within the contemplation of this invention that the bar could be extended to support all of the rings or that two bars could be utilized, one extending from each side, to support separate sets of rings.

In view of the fact that in this embodiment, the bar is retracted so that it no longer extends into the place of movement of the ring, it is desirable to provide a means for retaining the rings should the thread line break. I have provided such a means in the form of a retainer car 360 which extends laterally beneath the body 310 and passes through the plane of the rings. The retainer car is in close proximity to the ceramic

separator bars so that should the rings fall onto the retainer car, they can not slip out between the car and the ceramic bars. The retainer car is conveniently supported to the body 310 at the sidewalls thereof as best shown at 361, 362, FIG 9

It will be understood that various changes in the details, materials and arrangement of parts which have been herein described and illustrated in order to explain the nature of this invention, may be made by those skilled in the art within the principle and scope of the invention as expressed in the following claims.

I claim:

1. A tensioner, comprising: a plurality of rings; means for maintaining said rings in spaced relation; means for guiding a textile material through said rings; means engaging said rings to adjustably limit their travel in the direction of the radius of said rings, comprising a rod mounted in said tensioner and disposed to pass through said rings, said rod being movable in the axial direction with respect to said rings; and means provided in said device to engage said rod and retain it in a plurality of predetermined fixed lateral positions.

2. A tensioner comprising a plurality of rings, means for maintaining said rings in spaced relation, means for guiding a textile material through said rings, and means engaging said rings to adjustably limit their travel in the direction of the radius of said rings comprising a rod mounted in said tensioner

and disposed to pass through said rings, said rod being pivotally mounted to swing along the inner surface of said rings.

3. The device of claim 2 wherein said rod is movable to a plurality of predetermined fixed positions.

4. The invention of claim 2 wherein the means for retaining said rings in spaced relation comprises a plurality of U-shaped members, at least one member being disposed on each side of each ring.

10 5. The invention of claim 4 wherein said U-shaped members are connected at their free ends to a base, said base being disposed substantially vertically, said members being disposed in substantial alignment and in space relation to one another, and a plurality of smaller similarly configured U-shaped members are likewise disposed in said device in substantial alignment and fixedly attached at their free ends to said base, at least one of said smaller members being disposed inwardly and in the same plane of each of said larger U-shaped members.

15 6. The invention of claim 2 wherein a lever is connected at one end to said pivotally mounted rod, said lever being bent to engage said device upon appropriate rotation thereof and thereby position said rod, to remove said rings from contact with said textile material.
